UNITED STATES PATENT OFFICE.

THOMAS HOMER McANELLY, OF FINDLAY, OHIO.

DRAWING INSTRUMENT.

1,021,692.

Specification of Letters Patent. Patented Mar. 26, 1912.

Application filed May 8, 1911. Serial No. 625,803.

To all whom it may concern:

Be it known that I, THOMAS H. McANELLY, a citizen of the United States, and a resident of Findlay, in the county of Hancock and State of Ohio, have invented a new and Improved Drawing Instrument, of which the following is a full, clear, and exact description.

The object of the invention is to provide 10 a new and improved drawing instrument, combining a protractor, compass and measuring stick or straight edge for the use of mechanics, instructors and other persons, and especially serviceable for use in schools 15 when making drawings in geometry, physics and the like on a blackboard, the drawing instrument being simple, durable in construction and capable of being readily folded into small space or extended for drawing 20 straight lines, angles, circles, etc.

For the purpose mentioned, use is made of a straight edge made in foldable sections, of which one is mounted to swing laterally and provided with an adjustable pencil holder 25 for receiving a pencil for drawing circular lines.

A practical embodiment of the invention is represented in the accompanying drawing forming a part of this specification, in which 30 similar characters of reference indicate corresponding parts in all the views.

Figure 1 is a perspective view of the drawing instrument showing the sections extended to form a straight edge; Fig. 2 is a like 35 view of the same with the parts in folded position; Fig. 3 is a plan view of the first section; Fig. 4 is a similar view of part of the middle section; Fig. 5 is an enlarged cross section of the joint between the first 40 and middle sections on the line 5—5 of Fig. 2; Fig. 6 is a similar view of the pivotal connection between the middle and end sections, the section being on the line 6—6 of Fig. 1; Fig. 7 is an enlarged perspective 45 view of the pencil holder; Fig. 8 is a plan view of the drawing instrument, showing the parts in position for drawing circles; Fig. 9 is a like view of the drawing instrument showing the parts in position for indicating an angle; Fig. 10 is a plan view of a modified form of the drawing instrument; 50 and Fig. 11 is a face view of another modified form of the drawing instrument.

The drawing instrument consists essentially of a straight edge or measuring stick formed of a number of sections A, B and C,

of which the sections A and B are connected with each other by a transversely-extending pivot or a hinge D, to permit of folding the section A onto the section B as plainly indicated in Fig. 2. The sections B and C are pivotally connected with each other by a vertical pivot E, to permit of swinging the section C laterally into an extended position, as shown in Fig. 1, or onto the face of the 60 section B, as shown in Fig. 2, or into an angular position, as indicated in Figs. 8 and 9. The middle section B is sufficiently long to accommodate both end sections A and C when the latter are folded upon the middle 65 section B, as shown in Fig. 2, and the sections A, B and C are provided on both faces with graduations F representing linear measurement, preferably inches, and subdivisions, on one face, and metric measurement on the other face.

On the outer section C is mounted to slide lengthwise a pencil holder G, provided at its inner end with a bearing G' fitting on the section C, so as to guide the holder G in its 80 lengthwise movement, and the outer end of the holder G is provided with an eye or ring G² for the insertion of a pencil or other marking tool, to permit of drawing circles on swinging the end section C laterally relative to the section B, the pivot E being the center of the circle, as will be readily understood by reference to Fig. 8. An eye or ring G³ is attached to the bearing G' and projects laterally therefrom, so as to permit the 90 insertion of a pencil or other marking tool into the eye or ring G³ for drawing circles of a smaller radius, as indicated in Fig. 8.

Along one edge of the holder G are formed teeth or notches G⁴ adapted to engage a bearing H held on the outer end of the section C, and each of the said teeth or notches G⁴ is about of a length corresponding to one-quarter of an inch in conformity with the graduations F on the section C, and the said teeth are adapted to be hooked into the bearing H under which passes the holder G and secured to the outer end of the section C. When the holder G is in its innermost position, as indicated in Fig. 1, the eye 105 G² projects beyond the outer terminal of the section C and thus forms a finger piece adapted to be taken hold of by the operator for slightly moving the holder G laterally to disengage the corresponding tooth G⁴ 110 from the bearing H, and to allow of pulling the holder G outward or inward according

to the length of the radius of the circle to be drawn, by inserting the marking tool in the eye G^3 . The eye G^3 is preferably pivoted on the bearing G' to permit of swinging the 5 same onto the face of the holder when folding the drawing instrument.

In order to indicate the degrees of an angle represented by the sections B' and C' (see Fig. 10), use is made of a segmental 10 arm I provided with a degree scale and pivoted on the section B' . The segmental arm I is adapted to engage an open bearing J attached to the section C' , so that the segmental arm I indicates the degree of the angle 15 formed by the sections B' and C' when swung into an angular position one relative to the other, as shown in Fig. 10.

As shown in Fig. 11, the sections C^2 pivoted by the pivot E^2 to the middle section 20 B^2 is provided with a cutout portion filled by the pencil holder G^5 provided at its inner end with a bearing K , slidably engaging the section C^2 . The outward portion of the pencil holder G^5 longitudinally engages a 25 bearing K' attached to the section C^2 . The pencil holder G^5 is provided at its outer end with the eye G^6 for engagement by the marking tool the same as the eye G^2 previously mentioned.

30 The drawing instrument shown and described is very simple and durable in construction, composed of comparatively few parts, not liable to get out of order easily.

It is understood that the device is very 35 serviceable for use on blackboards in schools, to permit of the instructor or scholar to readily draw geometrical or other figures on the blackboard by the use of chalk or other tools inserted in the eyes G^2 , G^3 or G^6 .

40 Having thus described my invention, I claim as new and desire to secure by Letters Patent:

1. A drawing instrument, comprising a straight edge having a central section, and 45 end sections, one of said end sections being hinged to one end of the central section to fold thereon, the other end section being pivoted to the opposite end of the central section in superposed relation, said central section being of a length at least that of the 50

combined lengths of the end sections, whereby the free ends of the latter may be adjacent one another when both are moved to a folded position on the central section, and a pencil holder slidably mounted on the 55 swinging section and having an extending free end adapted to overlap a portion of the free end of the hinged end section in the folded position.

2. A drawing instrument comprising a 60 straight edge having a central section, and end sections, all having graduations along at least one edge, one of said end sections being hinged to one end of the central section to fold thereon, the other end section 65 being pivoted to the opposite end of the central section in superposed relation, said central section being of a length at least that of the combined lengths of the end sections, whereby the free ends of the latter may be 70 adjacent one another when both are moved to a folded position on the central section, and a pencil holder slidably mounted on the swinging section and having an extending ring, for the insertion of a pencil, adapted 75 to overlap a portion of the free end of the hinged end section in the folded position.

3. A drawing instrument, comprising a straight edge made in sections, one end section having a pivotal connection with the 80 adjacent section to permit of swinging the end section laterally, the sections having graduations representing linear measurement, and a pencil holder mounted to slide on the end section and having teeth along 85 one edge spaced apart according to the divisions of the said graduations, the said pencil holder being provided at the outer end with an integral ring, and near the inner end with a pivoted ring, the said rings being for the 90 insertion of a pencil for drawing circular lines of different radii.

In testimony whereof I have signed my name to this specification in the presence of two subscribing witnesses.

THOMAS HOMER McANELLY.
